VEHICLE DOOR LATCH DEVICE

CROSS REFERENCE

This application is the U.S. National Phase under 35 U.S.C. § 371 of International Application No. PCT/JP2015/050184, filed on Jan. 6, 2015, which claims the benefit of Japanese Application No. 2014-148042, filed on Jul. 18, 2014, the entire contents of each are hereby incorporated by reference.

FIELD

The present invention relates to a vehicle door latch device.

BACKGROUND

Conventionally, as described in, for example, Patent Literature 1, there is a vehicle door latch device including: a body accommodating therein an engagement mechanism, which restrains a door in a closed position by engaging with a striker on a vehicle body side; and a casing attached to the body and accommodating therein an operation mechanism, which has a locking and unlocking means that is able to switch over between an unlocked state where an engaged state of the engagement mechanism with the striker is releasable and a locked state where the engaged state is unreleasable. In this device, a waterproof seal, which is made of sponge or the like, soft, and band-shaped, is stuck onto a rear surface of the body, the rear surface of the body being above a striker advancing groove in the body and facing to an inner panel of the door, and onto a surface of a cover attached to the casing, the surface facing to the inner panel of the door, to prevent rainwater or the like that has gone inside the door from entering the striker advancing groove or the like from above.

CITATION LIST

Patent Literature

Patent Literature 1: Japanese Patent Application Publication No. 2013-139701

SUMMARY

Technical Problem

The door latch device described in Patent Literature 1 has a problem that workability upon the attachment of the waterproof seal is poor. Specifically, the waterproof seal has a band shape with a comparatively long dimension, before the attachment. Thus, when this waterproof seal is stuck with a double sided adhesive tape or the like that has been adhered on a reverse surface thereof, while being curved, along a shape of the body, from a rear surface top portion of the body towards a lower half portion thereof, and continuously being bent substantially at right angles towards the cover of the housing, a position where the waterproof seal is stuck may be deviated or wrinkles may be generated at the bent portion. Therefore, skill is required for the waterproof seal to be accurately stuck onto a fixed position, and workability upon the sticking is also poor.

Further, in the door latch device described in Patent Literature 1, a waterproof top cover (waterproof cover) that substantially covers a top half portion of a coupling portion

between the casing and the cover is installed. However, since a lower end of this top cover at a rear portion side thereof is only abutted against an upper surface of the waterproof seal, rainwater flowing down along a surface of the top cover on the rear portion side will flow towards above a rear surface side of the body along the upper surface of the waterproof seal. Therefore, if waterproofness of the waterproof seal is impaired due to temporal degradation or the like of the waterproof seal, there is a risk that rainwater may enter the striker advancing groove of the body from a gap between the inner panel of the door and the waterproof seal.

In view of the above described problems, an object of the present invention is to provide a vehicle door latch device enabling a waterproof seal to be accurately stuck onto a fixed position, workability upon the sticking to be improved, and even waterproofness to be improved.

Solution to Problem

The above-described problem is solved by the present invention as follows.

A first invention includes: a body in which an engagement mechanism is accommodated, the engagement mechanism being configured to restrain a door in a closed position by engaging with a striker on a vehicle body side, the body including a striker advancing groove, into which the striker is able to advance when the door is closed; a housing that has: an operation mechanism accommodating portion in which various components is accommodated; and a body accommodating portion provided consecutively on and substantially perpendicularly to the operation mechanism accommodating portion and configured to cover the body; a cover configured to close an opening of the operation mechanism accommodating portion; and a waterproof seal for preventing rainwater from entering the body. A seal sticking portion, at which an upper seal portion of the waterproof seal is stuck, is provided upward in a protruding manner at an upper portion of the body accommodating portion that is above the striker advancing groove; an upper positioning unit is provided at a lower edge and a side edge of the seal sticking portion, the side edge being on an extra-vehicle side, the upper positioning unit being configured to receive and position a lower surface and an end face of the upper seal portion, the end face being on the extra-vehicle side; and a side positioning unit, which is configured to position a side seal portion of the waterproof seal to be directed diagonally downward, is provided on a surface on an intra-vehicle side of the cover where the side seal portion is stuck, the side seal being provided in a continuous manner at the upper seal portion and being bent towards the cover.

In a second invention according to the first invention, a top waterproof cover, which is configured to cover a coupling portion between the operation mechanism accommodating portion and the cover, is provided above the housing, and a water shielding wall portion, which is configured to guide rainwater flowing down towards the body from an upper surface of the top waterproof cover in an intra-extra vehicle direction, is provided upward at an end portion on the body side of the top waterproof cover.

In a third invention according to the second invention, a side end on the extra-vehicle side of the water shielding wall portion is made adjacent to or to abut against a side end on the intra-vehicle side of the seal sticking portion such that rainwater is guided in an outward direction of a vehicle via the water shielding wall portion and the seal sticking portion.

In a fourth invention according to the second invention or the third invention, a side end on the intra-vehicle side of the water shielding wall portion is made continuous with an upper end of the side positioning unit such that rainwater guided to the intra-vehicle side by the water shielding wall portion is guided by an upper surface of the side positioning unit and flown down from the cover.

Advantageous Effects of Invention

According to the present invention, an upper positioning unit, which receives and positions a lower end of an upper seal portion and a side end on an extra-vehicle side of a waterproof seal, is provided at a lower edge and a side edge on an extra-vehicle side of a seal sticking portion provided in an upper portion of a body accommodating portion, and a side positioning unit, which positions a side seal portion of the waterproof seal, and which is directed in an oblique up-down direction, is provided on an intra-vehicle side of a cover. Therefore, a sticking start position and a sticking position of the waterproof seal are clarified, the waterproof seal is able to be positioned and accurately stuck onto a fixed position of the body accommodating portion and the cover, and workability upon the sticking is improved.

BRIEF DESCRIPTION OF DRAWINGS

FIG. 1 is an exploded perspective view illustrating an embodiment of a door latch device of the present invention.

FIG. 2 is a front view of the door latch device in FIG. 1 that has been assembled, as viewed from the front of a vehicle.

FIG. 3 is a rear view of the same door latch device.

FIG. 4 is a right side view of the same door latch device.

FIG. 5 is a left side view of the same door latch device.

FIG. 6 is a plan view of the same door latch device.

FIG. 7 is a left side view of the same door latch device in a state where a cover has been removed therefrom.

FIG. 8 is an enlarged perspective view of main parts before attachment of an auxiliary cover to the cover.

FIG. 9 is an enlarged perspective view after the attachment of the same auxiliary cover.

FIG. 10 is an enlarged perspective view of the auxiliary cover as viewed from a back surface thereof.

FIG. 11 is an enlarged cross sectional view along line XI-XI in FIG. 5.

FIG. 12 is an enlarged inner side view along line XII-XII in FIG. 4.

FIG. 13 is an enlarged cross sectional view along line XIII-XIII in the same figure.

FIG. 14 is an enlarged cross sectional view along line XIV-XIV in FIG. 5.

FIG. 15 is an enlarged cross sectional view along line XV-XV in the same figure.

FIG. 16 is a perspective view illustrating the door latch device as viewed from an intra-vehicle side and a waterproof seal before attachment.

FIG. 17 is a perspective view illustrating the same after the attachment of the waterproof seal.

FIG. 18 is an enlarged perspective view of a switch plate and a housing before attachment thereof, as viewed from the intra-vehicle side.

FIG. 19 is an enlarged perspective view of the same switch plate having been attached to the same housing.

FIG. 20 is a left side view of the same switch plate having been attached to the same housing.

FIG. 21 is a side view of main parts illustrating actions of an actuator when an actuation member is moved to a locked position and an unlocked position.

DESCRIPTION OF EMBODIMENTS

Hereinafter, an embodiment of the present invention will be described, based on the drawings.

As illustrated in FIG. 1 to FIG. 7, a door latch device 1

10 includes, in a front door (hereinafter, abbreviated as door) D on a left side of a vehicle: an engagement unit 2 fixed to a rear end portion of an inner panel D1 of the door D; an operation unit 3 integrally coupled with the engagement unit 2; and an actuator 4 provided in the operation unit 3.

15 As illustrated in FIG. 1 and FIG. 3, the engagement unit 2 includes: a body 5, which is made of synthetic resin, and is box-shaped; and a cover plate 7, which is fixed to a rear surface of the body 5, is fixed, together with the body 5, with a plurality of bolts 6, to a rear portion of the inner panel D1

20 in the door D, and is made of metal. In an internal space between the body 5 and the cover plate 7, an engagement mechanism 9, which restrains the door in a closed state, is accommodated. The body 5 and the cover plate 7 are provided with a striker advancing groove 10, into which a striker 8 advances in response to the door D being closed, respectively.

25 The engagement mechanism 9 has a latch 12, and a locking plate 14. The latch 12 is biased in an opening direction by a spring 16 wound around a pivot shaft 11. The latch 12 is pivotally supported by the pivot shaft 11 in the body 5, and is engaged with and disengaged from the striker 8 on an extra-vehicle side. The latch 12 is biased in the opening direction by the spring 16 wound around the pivot shaft 11. The locking plate 14 prevents the latch 12 from pivoting in the opening direction of the latch 12 (anticlockwise in FIG. 3) by engaging with an outer peripheral edge of the latch 12.

30 The locking plate 14 has been pivoted once, in association with the latch 12 pivoting from an open position to a closed position, from an engaged position where the latch 12 is engaged with the striker 8, in a releasing direction against a biasing force of a spring 15 that biases the locking plate 14 in an engaging direction, and then engages with the outer peripheral edge of the latch 12 by the biasing force of the spring 15 to prevent the latch 12 from pivoting in the opening direction. Further, when a later described opening lever 18 is released actuated based on an operation of an outside handle (illustration omitted) for opening the door, the outside handle being provided on the extra-vehicle side of the door D, or based on an operation of an inside handle (illustration omitted) provided on the intra-vehicle side thereof, the locking plate 14 pivots in the releasing direction from an engaged position where the locking plate 14 is engaged with the outer peripheral edge of the latch 12, so 35 that the door becomes openable.

40 On a front surface side of the body 5, a base plate 17, which is fixed to a housing 23 described later, is L-shaped in its planar view, and is made of metal, is attached. Further, on the front surface side of the body 5: the opening lever 18 that is fixed to a pivot shaft 13 so as to integrally pivot with the locking plate 14; a locking and unlocking lever 19 that forms a part of a locking and unlocking mechanism; an outside lever 21 that is pivotally supported by a pivot shaft 20, and is coupled to the outside handle on the extra-vehicle side of the door via an operating force transmission member S; and a sub lever 22 that is disposed between the locking and unlocking lever 19 and the outside lever 21 and forms

a part of the locking and unlocking mechanism, are installed. The sub lever 22 has a first lever 22a and a second lever 22b. A lower end portion of the first lever 22a is pivotally fitted to a free end portion of the outside lever 21. An elongated hole 22c along an up-down direction and provided in an upper end portion of the first lever 22a is slidably coupled to a protruding portion 19b provided in a lower end portion of the locking and unlocking lever 19.

The locking and unlocking lever 19 is able to be switched over between a locked state and an unlocked state, based on operation of a locking knob (illustration omitted), which is provided on the intra-vehicle side of the door, for locking and unlocking operation, and based on operation of a key cylinder (illustration omitted) provided on the extra-vehicle side of the door. A lower end portion of the second lever 22b is pivotally fitted to the lower end portion of the first lever 22a.

A coupling portion 19a of the locking and unlocking lever 19, the coupling portion 19a being provided on a front surface of the locking and unlocking lever 19 and directed to the front, is coupled to a later described actuation member 52 of the actuator 4 when the engagement unit 2 is attached to the operation unit 3. Thereby, in synchronization with actuation of the actuation member 52, the locking and unlocking lever 19 is able to be switched over between the locked state and the unlocked state.

The operation unit 3 includes the housing 23, which is substantially L-shaped in its planar view and is made of synthetic resin. The housing 23 includes a first case 25, a second case 26, and a cover 27 made of synthetic resin. The first case 25 is arranged adjacent to a side surface of the inner panel D1 in the door D and has an operation mechanism accommodating portion 24 that is open on the intra-vehicle side thereof. The second case 26 is a body accommodating portion, which extends from a rear end portion of an intermediate portion along an up-down direction in the first case 25, substantially perpendicularly thereto in an outward direction of the vehicle, and to which the engagement unit 2 is fixed to a rear surface side thereof. The cover 27 closes an opening of the operation mechanism accommodating portion 24 of the first case 25, while exposing the vicinity of the striker advancing groove 10 of the body 5 that accommodates the engagement unit 2. In the operation mechanism accommodating portion 24 of the first case 25, electrical components, such as a later described operation mechanism 28 including the actuator 4, a switch plate 46, and switches 60 and 61, are installed. The housing 23 excluding the cover 27 is formed of, for example, polyacetal resin (POM), which is comparatively inexpensive and hard.

On an upper portion of the operation mechanism accommodating portion 24 of the first case 25, an outer peripheral wall 251, which protrudes in the inward direction of the vehicle, is formed, and plural protruding portions 252 are formed on an outer surface of this outer peripheral wall 251. Further, on an outer peripheral wall 271 of the cover 27, the outer peripheral wall 271 facing to the outer peripheral wall 251 of the first case 25, plural engagement pieces 272 engageable with the protruding portions 252 are provided in a protruding manner. After the operation mechanism 28 is installed in the operation mechanism accommodating portion 24, the respective engagement pieces 272 are engaged with the respective protruding portions 252 of the operation mechanism accommodating portion 24, and it is brought into contact with the outer peripheral walls 251 and 271 with each other, whereby the cover 27 is fixed to the first case 25 so as to cover the operation mechanism 28 accommodated in the operation mechanism accommodating portion 24.

As illustrated in FIG. 1 and FIG. 7, at a front lower portion of the operation mechanism accommodating portion 24 in the first case 25, two upper and lower conduit fixing portions 29 and 30, which are concave shaped, and which is open on the intra-vehicle sides thereof, are provided. Front end portions of these conduit fixing portions 29 and 30 protrude more forward than front surfaces of the first case 25 and a top waterproof cover 42 described later. On inner wall surfaces of both of the conduit fixing portions 29 and 30, the inner wall surfaces being opposite to each other, elastic claw pieces 29a and 29a, and 30a and 30a, which are elastically deformable in a direction orthogonal to an arrangement direction of conduits 32 and 34 described later, are respectively provided in a protruding manner.

To the upper conduit fixing portion 29, a large diameter end portion 32a of the conduit 32, through which a cable 31 is inserted, is fitted, and the large diameter end portion 32a is fixed by the elastic claw pieces 29a and 29a. One end of the cable 31 is coupled to the locking knob for the locking and unlocking operation provided on the intra-vehicle side of the door, and the other end thereof is coupled to a knob lever 55 described later, respectively. To the lower conduit fixing portion 30, a large diameter end portion 34a of the conduit 34, through which a cable 33 is inserted, is fitted, and the large diameter end portion 34a is fixed by the elastic claw pieces 30a and 30a. One end of the cable 33 is coupled to the inside handle (illustration omitted) on the intra-vehicle side and the other end thereof is coupled to an inside lever 57 described later.

As illustrated in FIG. 1 and FIG. 8, at a portion of the cover 27, the portion facing to the conduit fixing portions 29 and 30 of the first case 25, openings 35 and 35, which are open in an intra-extra vehicle direction and forward, are formed. The large diameter end portions 32a and 34a of the conduits 32 and 34 are fitted into the conduit fixing portions 29 and 30 through these upper and lower openings 35. A dimension of forward protrusion of the cover 27 between the upper and lower openings 35 and 35 is very small.

As illustrated in FIG. 1, FIG. 4, and FIG. 13, on a lower surface of the lower conduit fixing portion 30, a holding piece 36 and an engagement protruding portion 37 are formed, the holding piece 36 being open in the intra-extra vehicle direction and U-shaped in its side view, and the engagement protruding portion 37 gradually sloped downwards in the outward direction of the vehicle. On a front lower portion of the cover 27 opposite to the holding piece 36, an elastic engagement piece 38 having an engagement hole 38a is provided in a protruding manner towards the outward direction of the vehicle. When the cover 27 is attached to the first case 25, this elastic engagement piece 38 is fitted to the holding piece 36, and the engagement hole 38a is elastically engaged with the engagement protruding portion 37, and thereby, a lower portion of the cover 27 is fixed to the first case 25. Slightly below the elastic engagement piece 38 in the cover 27, a fitting hole 39, into which an insertion piece 406 of an auxiliary cover 40 described later is fittable and which is oblong, is formed oppositely to an internal space of the holding piece 36.

As illustrated in FIG. 1 and FIG. 8, on a lower side surface 60 on the intra-vehicle side of the cover 27, a first rainwater guide protruding portion 273, a second rainwater guide protruding portion 274, and a third rainwater guide protruding portion 275, where rainwater flowing down along a side surface on the intra-vehicle side of the cover 27 is guided to 65 be prevented from heading towards the upper and lower openings 35, are provided in a protruding manner in an inward direction of the vehicle. The first rainwater guide

protruding portion 273 is formed at a position a little separated from a rear portion side of the upper opening 35, so as to be sloped from the upper front to the lower rear. The second rainwater guide protruding portion 274 is formed to be continuous with an upper edge of the upper opening 35 a little separated from and below the first rainwater guide protruding portion 273, and to be sloped to the lower rear with a predetermined interval kept from the first rainwater guide protruding portion 273. The third rainwater guide protruding portion 275 is formed to be sloped to the upper front, above a rear portion side of the lower opening 35 and below a rear portion side of the second rainwater guide protruding portion 274, and such that a lower half portion thereof extends substantially vertically downward at the rear of and adjacent to the lower opening 35.

The rainwater flowing down along the side surface on the intra-vehicle side of the cover 27 is received by the first and second rainwater guide protruding portions 273 and 274 and guided to the lower rear. Rainwater flowing down from lower ends of the first and second rainwater guide protruding portions 273 and 274 is received by the third rainwater guide protruding portion 275 and guided towards a lower end of the cover 27. Therefore, there will be no risk that rainwater that has entered the door will enter the housing 23 from the upper and lower openings 35 along the side surface on the intra-vehicle side of the cover 27. An outer peripheral wall portion 402 of the auxiliary cover 40 described later is inserted between the first rainwater guide protruding portion 273 and the second rainwater guide protruding portion 274. Due to the labyrinth action caused by the first and second rainwater guide protruding portions 273 and 274 and the outer peripheral wall portion 402 of the auxiliary cover 40, rainwater is prevented from going into the openings 35 (see FIG. 14).

On the lower side surface on the intra-vehicle side of the cover 27, the auxiliary cover 40, which closes the upper and lower openings 35 to prevent rainwater from entering therefrom and is made of synthetic resin, is installed. As enlarged and illustrated in FIG. 5 and FIG. 8 to FIG. 10, the auxiliary cover 40 is roughly trapezoidal in its side view with a size that is able to close, with allowance, the upper and lower openings 35 of the cover 27 and the upper and lower conduit fixing portions 29 and 30 of the first case 25. At an upper and lower portions of a front end portion of the auxiliary cover 40, pressing pieces 401 and 401, which are able to press an outer peripheral surface on the intra-vehicle side of the large diameter end portions 32a and 34a of the conduits 32 and 34 fitted to the conduit fixing portions 29 and 30, are formed. The upper and lower pressing pieces 401 on a front end side also serve as a cover that covers front side openings of the conduit fixing portions 29 and 30, from the front and leaving insertion portions of the conduits 32 and 34.

As illustrated in a back view of FIG. 10, at an upper portion of the auxiliary cover 40, the outer peripheral wall portion 402, which is inserted between the above described first rainwater guide protruding portion 273 and the second rainwater guide protruding portion 274, has an outer end surface abuttable against the side surface on the intra-vehicle side of the cover 27, and is rib-shaped, is formed. At a lower portion of a rear edge of the auxiliary cover 40, an outer peripheral wall portion 403, which has an outer end surface abuttable against the side surface on the intra-vehicle side of the cover 27, at the rear of and adjacent to the above described third rainwater guide protruding portion 275, and is rib-shaped, is formed. Each of the outer peripheral wall portions 402 and 403 is formed in the outward direction of the vehicle. Further, an upward protruding piece 404, which

is covered by a later described intra-vehicle side water shielding wall portion 426 of the top waterproof cover 42 and is in a front-rear direction, is integrally formed with an upper end of the auxiliary cover 40 which is continuous with the outer peripheral wall portion 402.

Between the upper and lower pressing pieces 401 and 401, on a back surface (surface on the extra-vehicle side) of the front end portion of the auxiliary cover 40, a pair of front and rear elastic engagement pieces 405 and 405 having, at 10 distal end portions thereof, engagement claw portions 405a directed in opposite directions (outward directions) from each other are provided in a protruding manner in the outward direction of the vehicle. When the auxiliary cover 40 is attached to the cover 27, as illustrated in FIG. 8, these 15 elastic engagement pieces 405 are fitted into a rectangular opening 253 formed in a front end portion of the first case 25 between the upper and lower conduit fixing portions 29 and 30. When this is done, the engagement claw portions 405a are elastically engaged with end faces on the extra- 20 vehicle side of a pair of engagement pieces 254 and 254 protruding in the outward direction of the vehicle from front and rear opening edges of the opening 253 (see FIG. 12).

At a lower end portion on the back surface of the auxiliary cover 40, the insertion piece 406, which is directed in the 25 outward direction of the vehicle and is for positioning, is provided in a protruding manner. When the auxiliary cover 40 is attached to the cover 27, this insertion piece 406 penetrates through the fitting hole 39 of the cover 27 and is fitted to the above described U-shaped holding piece 36 in 30 the first case 25 (see FIG. 13).

On a rear surface of the outer peripheral wall portion 403 at the lower portion of the auxiliary cover 40, an engagement claw 403a is provided in a protruding manner. This engagement claw 403a is engageable with a reverse surface (surface on the extra-vehicle side) of an engagement protruding portion 276, which is, as illustrated in FIG. 5, FIG. 8, and FIG. 9, formed to protrude to the intra-vehicle side at a rear end lower portion of the cover 27 and has an L-shaped cross section in its planar view, when the auxiliary cover 40 is 40 attached to the cover 27 (see FIG. 15).

As illustrated in FIG. 8 and FIG. 10, in a top portion rearward in the auxiliary cover 40, an engagement hole 407, which is oblong, is formed. At a central portion on an upper surface in this engagement hole 407, an engagement protruding portion 408, which has a short dimension than a vertical dimension of the engagement hole 407 and is directed upward, is formed. On a surface on the intra-vehicle side of the cover 27 opposite to this engagement hole 407, a fitting protruding portion 277 fittable into the engagement hole 407 is provided in a protruding manner. On a lower surface of this fitting protruding portion 277, as illustrated in a cross sectional view in FIG. 14, an engagement hole 277a, with which the engagement protruding portion 408 is engageable from therebelow and which is recessed upward, 55 is formed. Shaft holes 41 and 41, into which a distal end portion of a support shaft 56 of the later described inside lever 57 provided in the first case 25 is fitted, are provided at the cover 27 and the auxiliary cover 40 (see FIG. 1).

To attach the auxiliary cover 40 to the cover 27, the pair 60 of elastic engagement pieces 405 provided in the auxiliary cover 40 are fitted into the opening 253 of the first case 25, and the engagement claw portions 405a of both the elastic engagement pieces 405 are elastically engaged with the respective engagement pieces 254 of the first case 25 (see FIG. 12). The engagement claw 403a on a rear side of the auxiliary cover 40 is engaged with the reverse surface of the engagement protruding portion 276 of the cover 27 (see FIG.

15), and further, the engagement hole 407 in the rear upper portion of the auxiliary cover 40 is fitted to the fitting protruding portion 277 of the cover 27 and the engagement protruding portion 408 in the engagement hole 407 is engaged with the engagement hole 277a of the fitting protruding portion 277 (see FIG. 14). Further, simultaneously therewith, the insertion piece 406 at the lower end portion of the auxiliary cover 40 is penetrated through the fitting hole 39 of the cover 27 and fitted to the U-shaped holding piece 36 in the first case 25 (see FIG. 13).

Thereby, even without use of a fixing means, such as screws, the auxiliary cover 40 is able to be unmovingly attached, without loosening, to the first case 25 and the cover 27 of the housing 23, so as to abut against or be adjacent to the side surface on the intra-vehicle side of the cover 27, in a state of being sloped slightly to the upper front. Further, since the upper and lower conduit fixing portions 29 and 30 of the first case 25 and the upper and lower openings 35 of the cover 27 are closed by the auxiliary cover 40, there will be no risk that rainwater flowing down along the side surface on the intra-vehicle side of the cover 27 will enter the housing 23. Furthermore, as described above, by the labyrinth action caused by the first and second rainwater guide protruding portions 273 and 274 and the outer peripheral wall portion 402 of the auxiliary cover, rainwater flowing down along the side surface on the intra-vehicle side of the cover 27 is also prevented from entering the housing 23 from a gap between the cover 27 and the auxiliary cover 40. After the attachment of the auxiliary cover 40, since a visor-like front side water shielding wall portion 425 of the later described top waterproof cover 42 is positioned directly above the front end portion thereof, rainwater is prevented from entering the housing 23 from insertion portions of the conduits 32 and 34 in the conduit fixing portions 29 and 30 (see FIG. 5 and FIG. 9).

As illustrated in FIG. 1 to FIG. 6, FIG. 16, and FIG. 17, in an area from an upper surface of the first case 25 and the cover 27 in the housing 23 to the upper conduit fixing portion 29, the top waterproof cover 42, which is for preventing rainwater from entering the operation mechanism accommodating portion 24 of the first case 25 and is made of synthetic resin, is provided. This top waterproof cover 42 is integrally formed of an upper side covering portion 421, with a rear surface thereof slightly sloped rearward, and a front side covering portion 422. The upper side covering portion 421 covers the whole area of an upper surface and a front and rear vertical surfaces near the upper surface, of the operation mechanism accommodating portion 24 and the cover 27. The front side covering portion 422 covers a substantial upper half of a front surface and a vertical surface near the front surface, of the operation mechanism accommodating portion 24 and the cover 27.

Plural fitting holes 43 are formed at a pair of front and rear downward pieces 421a of the upper side covering portion 421 and a pair of front and rear rearward pieces 422a of the front side covering portion 422, and these fitting holes 43 are engaged with plural protruding portions 44 provided on an outer surface of the first case 25 and the cover 27. Thereby, the top waterproof cover 42 covers a top portion and a front portion of a coupling portion between the first case 25 and the cover 27, and is fixed so as to sandwich top portions of the first case 25 and cover 27 (see FIG. 11).

As illustrated mainly in FIG. 5, FIG. 6, and FIG. 16, at a rear end of the top waterproof cover 42, a water shielding wall portion 423, which is sloped slightly to the upper front, is mountain-shaped in its rear view, and is directed in the up-down direction, is integrally formed therewith. The water

shielding wall portion 423 is configured to be continuous with a lower rear end of the upper side covering portion 421 and to be a little separated from the rear surface of the upper side covering portion 421. An intra-extra vehicle direction dimension of this water shielding wall portion 423 is a little greater than a width dimension of the upper side covering portion 421, and a height of its apex is substantially equal to that of an upper surface of the upper side covering portion 421. Further, on an opposing surface of a central portion 10 between the water shielding wall portion 423 and the upper side covering portion 421, a partition piece 424 directed in the up-down direction is provided. By the provision of the water shielding wall portion 423 and the partition piece 424, as illustrated with arrows in FIG. 6, rainwater flowing down 15 from the upper surface to a rear surface side of the upper side covering portion 421 is guided to flow in the outward direction and inward direction of the vehicle, and thus the rainwater is prevented from flowing down to an upper portion side of the second case 26 installed with the engagement unit 2. As a result, even if the later described waterproof seal 45 is deteriorated by temporal change and its 20 waterproofness is ruined, there will be no risk that rainwater will enter the engagement unit 2 or the housing 23.

As illustrated in FIG. 4, FIG. 5, FIG. 8, FIG. 9, and FIG. 25 11, at a lower end on a front side of the top waterproof cover 42, the front side water shielding wall portion 425, which is visor-like, and the intra-vehicle side water shielding wall portion 426 and an extra-vehicle side water shielding wall portion 427, which have inverted L-shaped cross sections, 30 are formed to be continuous respectively with a lower end of the front side covering portion 422 and lower ends of the extra-vehicles side and intra-vehicle side rearward pieces 422a. An intra-extra vehicle direction width dimension of the front side water shielding wall portion 425 is a little 35 greater than an intra-extra vehicle direction dimension of the housing 23, and the front side water shielding wall portion 425 is sloped to the lower front so as to be able to cover directly above the conduit fixing portion 29 in the first case 25 and an upper end portion on a front side of the auxiliary cover 40. Thereby, rainwater flowing down along the front side covering portion 422 of the top waterproof cover 42 is 40 prevented from entering the housing 23 from the insertion portions of the conduits 32 and 34 in the conduit fixing portions 29 and 30.

45 A front-rear direction length of the intra-vehicle side water shielding wall portion 426 is substantially equal to a front-rear direction length of the upward protruding piece 404 at the upper end of the auxiliary cover 40, and the upward protruding piece 404 is covered by the intra-vehicle side water shielding wall portion 426 when the top waterproof cover 42 is attached to the housing 23. Thereby, rainwater flowing down along a side surface on the intra-vehicle side of the cover 27 and top waterproof cover 42 is guided towards a surface of the auxiliary cover 40, and rainwater that has gone into the gap between the cover 27 and auxiliary cover 40 is prevented from entering the housing 23 from the opening 35 formed in the cover 27.

As illustrated in FIG. 1 to FIG. 6, FIG. 16, and FIG. 17, above a rear surface side of the engagement unit 2, the waterproof seal 45 is attached to an upper end portion on a rear surface side of the second case 26 and to the side surface on the intra-vehicle side of the cover 27. This waterproof seal 45 is, for example, a compressible, sponge-like, and band-shaped with a sufficient thickness. By the waterproof seal 45 being bent towards the second case 26 and the cover 27, an upper seal portion 45a that covers an upper portion on the rear surface side of the engagement unit 2 and a side seal

portion **45b** that covers an upper front portion on the intra-vehicle side of the engagement unit **2** are formed. As illustrated in FIG. 6, the upper seal portion **45a** is opposite to a rear surface of the inner panel **D1** in the door **D**, and the side seal portion **45b** is opposite to an inner surface of the inner panel **D1**. The waterproof seal **45** is stuck with a double sided adhesive tape stuck on a reverse surface thereof or an adhesive applied onto the reverse surface.

Above the rear surface of the engagement unit **2** in the second case **26**, a seal sticking portion **261**, to which a reverse surface (front surface) of the upper seal portion **45a** of the waterproof seal **45** is stuck, is provided. The seal sticking portion **261** is provided upward in a protruding manner so as to be sloped a little downward in the outward direction of the vehicle. At a side end and a lower end on the extra-vehicle side of this seal sticking portion **261**, a first positioning portion **262**, which receives and positions an end face on the extra-vehicle side of the waterproof seal **45** and is directed in the up-down direction, and a second positioning portion **263**, which receives and positions a lower surface of the waterproof seal **45** and is directed in the intra-extra vehicle direction, are respectively provided rearward and integrally therewith in a protruding manner. The first positioning portion **262** and the second positioning portion **263** form an upper positioning unit. Further, the seal sticking portion **261** also serves as a water shielding wall that prevents rainwater flowing down from a rear surface of the top waterproof cover **42** from flowing down towards an upper portion on the engagement unit **2** side. That is, as illustrated with the arrows in FIG. 6, the seal sticking portion **261** is provided so as to abut against or be adjacent to a side end on the extra-vehicle side of the water shielding wall portion **423** at the rear end of the top waterproof cover **42**. Thereby, rainwater flowing down from the rear surface of the top waterproof cover **42** is guided in the outward direction of the vehicle along the seal sticking portion **261** and is prevented from flowing down to above the engagement unit **2**.

At a central portion on the side surface on the intra-vehicle side of the cover **27**, that is, at an upper portion separated from an opening on the intra-vehicle side of the striker advancing groove **10** formed in the body **5** of the engagement unit **2**, a third positioning portion **264**, which is for positioning the side seal portion **45b** of the waterproof seal **45** and is rib-shaped, is provided. The third positioning portion **264** is provided in a protruding manner, so as to be sloped diagonally to the lower front from around a rear end portion of the top waterproof cover **42**. Although the third positioning portion **264** is not continuously formed, the third positioning portion **264** may of course be continuously formed. An upper end of the third positioning portion **264** is continuous with a side end on the intra-vehicle side of the water shielding wall portion **423** of the top waterproof cover **42**. Further, at a central portion on the side surface on the intra-vehicle side of the cover **27**, the central portion being separated from a lower portion of the third positioning portion **264**, a fourth positioning portion **265**, which is for positioning a lower end portion of the side seal portion **45b** of the waterproof seal **45** and has a short dimension, is provided. The fourth positioning portion **265** is provided in a protruding manner in parallel with the third positioning portion **264**. The third positioning portion **264** and the fourth positioning portion **265** form a side positioning unit.

To attach the waterproof seal **45**, first, the end face and the lower surface on the extra-vehicle side of the upper seal portion **45a** are respectively abutted against the first positioning portion **262** and second positioning portion **263** of

the second case, to position the upper seal portion **45a** in the intra-extra vehicle direction and up-down direction. In this state, the reverse surface of the upper seal portion **45a** is stuck onto the rear surface of the seal sticking portion **261** and the lower portion on the rear surface of the top waterproof cover **42**.

Subsequently, while positioning the side seal portion **45b** bent towards the cover **27** in the up-down direction and front-rear direction by extending the side seal portion **45b** diagonally to the lower front along the third positioning portion **264** of the cover **27** and positioning the lower end portion of the side seal portion **45b** between the third positioning portion **264** and the fourth positioning portion **265**, the reverse surface of the side seal portion **45b** is stuck onto the side surface on the intra-vehicle side of the cover **27**. When this is done, an upper end portion of the first rainwater guide protruding portion **273** provided in the cover **27** is able to serve as a guide of an end point of a sticking position of the side seal portion **45b**, by the upper end portion being regarded as serving as a fifth positioning portion that positions the lower end of the side seal portion **45b**. The lower end of the side seal portion **45b** may be stuck so as to abut against or be adjacent to the upper end portion of the first rainwater guide protruding portion **273**.

Thereby, as mainly illustrated in FIG. 17, the upper portion on the rear surface side and the upper front on the intra-vehicle side of the striker advancing groove **10** formed in the cover plate **7** of the engagement unit **2** and the body **5** are covered by the waterproof seal **45**. When the door latch device **1** is installed in the door **D**, as illustrated in FIG. 6, the upper seal portion **45a** and the side seal portion **45b** are compressed by respectively abutting against the rear surface of the inner panel **D1** of the door **D** and the inner surface of the inner panel **D1**. Therefore, a gap formed between the engagement unit **2** and the inner panel **D1** is closed by the waterproof seal **45**, and rainwater that has gone inside the door **D** is prevented from going into the striker advancing groove **10** from above.

Further, as described above, on the rear surface top portion of the top waterproof cover **42**, the water shielding wall portion **423**, which guides rainwater flowing down from the rear surface of the top waterproof cover **42** in the intra-extra vehicle direction, is provided, and the seal sticking portion **261** in the upper portion of the second case **26** has a function as a water shielding wall that guides rainwater flowing down from the rear surface of the top waterproof cover **42** to the extra-vehicle side, and thus an amount of rainwater flowing towards the rear surface side of the engagement unit **2** becomes extremely small. Therefore, only the upper seal portion **45a** of the waterproof seal **45** stuck on the rear surface side of the engagement unit **2**, the upper seal portion **45a** covering the top portion on the rear surface side of the engagement unit **2**, will be sufficient, and as compared to waterproof seals stuck onto conventional door latch devices, a length of the waterproof seal **45** is able to be made shorter and its sticking ability is able to be improved. Rainwater guided towards the intra-vehicle side of the cover **27** by the water shielding wall portion **423** of the top waterproof cover **42** flows down to the lower front along the upper surface of the third positioning portion **264**, and thus an amount of rainwater flowing towards the side seal portion **45b** of the waterproof seal **45** becomes extremely small.

Further, the first to fourth positioning portions **262**, **263**, **264**, and **265** are provided on the rear surface of the second case **26** and the side surface on the intra-vehicle side of the cover **27**, so that positioning upon sticking of the waterproof

seal 45 is enabled. Thereby, a sticking start position and a sticking position for the waterproof seal 45 are clarified, and the waterproof seal 45 is able to be easily stuck to a fixed position on the engagement unit 2 and the cover 27, and thus workability upon the sticking is improved.

As illustrated in FIG. 7 and FIG. 18 to FIG. 20, inside the operation mechanism accommodating portion 24 of the first case 25 in the housing 23, the switch plate 46 directed in the up-down direction is installed. This switch plate 46 is integrally formed together with a female connector portion 461, with plural conductive plates 47 being embedded in a synthetic resin 462 by insert molding, the plural conductive plates 47 being conductible with electrical components, such as a motor 48, the rotary switch 60, and the limit switch 61, which will be described later and are incorporated in the operation mechanism accommodating portion 24, and with plural terminal portions 471 of the female connector portion 461 and a conducting portion to the motor 48, the rotary switch 60, and the limit switch 61 being exposed. The synthetic resin 462 used in the insert molding is preferably formed of, for example, a resin mixture of polybutyrene terephthalate resin (PBT resin) and ABS resin, the resin mixture being added with glass fiber.

At an upper end portion and an up-down direction intermediate portion of the switch plate 46, a rotary switch attachment portion 463 and a limit switch attachment portion 464 having a pair of upper and lower switch holding pieces 464a and 464a directed forward are respectively formed, integrally with the synthetic resin 462. In the attachment portions 463 and 464, engagement holes 465 in the intra-extra vehicle direction are formed. Further, slightly above the limit switch attachment portion 464, an abutment piece 466, which is abuttable against the reverse surface of the cover 27 when the above described cover 27 is attached to the first case 25, is provided in a protruding manner in the inward direction of the vehicle. The upper and lower switch holding pieces 464a of the limit switch attachment portion 464 also serve as an engaged unit engageable with a later described first engagement portion 256 provided in the first case 25. A terminal of the rotary switch 60 attached to the rotary switch attachment portion 463 and a terminal of the limit switch 61 attached to the limit switch attachment portion 464 are fixed by resistance welding to the conducting portion of the conductive plates 47 exposed from the synthetic resin 462 in the switch plate 46.

The female connector portion 461 is formed to be directed diagonally to the lower front, and flange portions 461a and 461a, which are a little separated from each other, are formed at a proximal end portion (root portion) thereof. At upper and lower portions in an engagement groove portion 461b between opposite surfaces of the flange portions 461a and 461a, engaged portions 467 and 467, which are engageable with engagement claws 257a of a pair of second engagement portions 257 provided at a lower end portion of the first case 25 and described later, are provided.

At an upper portion and an intermediate portion on a side surface on the intra-vehicle side of the first case 25, shaft-like protruding portions 255 and 255, with which the upper and lower engagement holes 465 of the switch plate 46 are engaged by fitting, are provided in a protruding manner. Further, at the intermediate portion on the side surface on the intra-vehicle side of the first case 25, a pair of upper and lower first engagement portions 256 and 256, with and by which the limit switch attachment portion 464 of the switch plate 46 is elastically engaged and held, are formed oppositely to each other with the lower protruding portion 255 disposed therebetween.

Furthermore, at a portion in the first case 25 opposite to a proximal end portion of the female connector portion 461, the pair of second engagement portions 257 and 257 and the engagement claws 257a and 257a are provided, the engagement claws 257a being provided downward in a protruding manner on opposite surfaces of these second engagement portions 257. The pair of second engagement portions 257 are fitted to the upper and lower portions of the engagement groove portion 461b of the female connector portion 461. These engagement claws 257a and 257a are provided inward in a protruding manner on the opposite surfaces of both of the second engagement portions 257, and are engageable with end surfaces on the intra-vehicle side of the pair of engaged portions 467 and 467 in the engagement groove portion 461b. The upper and lower protruding portions 255 and the pairs of upper and lower first engagement portions 256 and second engagement portions 257, which are provided in the first case 25; and the upper and lower engagement holes 465, the switch holding pieces 464a, and the engaged portions 467, which are provided in the switch plate 46 and the female connector portion 461, form engagement means.

When the switch plate 46 is installed in the first case 25, the upper and lower engagement holes 465 are pushed and fitted to the upper and lower protruding portions 255 of the first case 25, and the upper and lower switch holding pieces 464a serving as the engaged unit in the limit switch attachment portion 464 are fitted and elastically held between the upper and lower first engagement portions 256. Further, the engagement groove portion 461b of the female connector portion 461 is pushed to the pair of second engagement portions 257 in the lower end portion of the first case 25, and the engagement claws 257a on the opposite surfaces of the second engagement portions 257 are engaged with the end faces on the intra-vehicle side of the pair of engaged portions 467 in the engagement groove portion 461b. Thereby, as illustrated in FIG. 19 and FIG. 20, the switch plate 46 is stably attached to the side surface on the intra-vehicle side of the first case 25 without floating or loosening thereof being caused. Furthermore, just by pushing the switch plate 46 towards the first case 25, the plural upper and lower engagement means are able to be engaged with each other, installation work of the switch plate 46 in the first case 25 becomes efficient.

As described above, when the switch plate 46, which is separately formed from the housing 23 by insert molding, is installed in the first case 25, the insert molding process needs to be performed only once. That is, conventionally, two insert molding processes, which are a primary process of forming the switch plate 46 itself by insert molding and a secondary process of fixing this switch plate 46 to the housing 23 by insert molding, have been required. In contrast, if only a single insert molding process is needed, since the manufacturing cost for molds and the man-hour are reduced, the cost of the door latch device is reduced.

Further, since different synthetic resin materials are able to be used in forming the housing 23 and the switch plate 46, options of materials are increased. Accordingly, the material cost is able to be saved by, for example, forming the housing 23, which is large, with an inexpensive synthetic resin material. Further, by forming the female connector portion 461 integrally with the switch plate 46, excellent water-proofness is able to be achieved.

Next, a configuration of the above described operation mechanism 28 including the actuator 4 for locking and unlocking operation, the operation mechanism 28 being incorporated in the operation mechanism accommodating

portion 24 of the first case 25 in the housing 23, will be described. As illustrated in FIG. 1 and FIG. 7, the actuator 4 includes: the motor 48, which is actuated based on operation of a remote control switch or the like (not illustrated) by being connected to the above described switch plate 46 and is normally and reversely rotatable; a worm 49, which is fixed to a rotary shaft 48a of the motor 48, the rotary shaft 48a being directed upwards; a worm wheel 51, which is driven by the worm 49, and has a cross-shaped driving portion 50 that is integrally fixed to one of rotary surfaces on the intra-vehicle side thereof; and the actuation member 52, which is moved to an upper locked position and a lower unlocked position by the driving portion 50 and is in the up-down direction. The motor 48 is accommodated without play, on a front portion side in the operation mechanism accommodating portion 24, to be directed in the up-down direction. The worm wheel 51 is freely rotatably supported by a support shaft 53 provided in a protruding manner on a side surface on the intra-vehicle side of the operation mechanism accommodating portion 24.

The knob lever 55 forming a part of the operation mechanism 28 is pivotally supported by a support shaft 54 provided in a protruding manner from a central portion of the operation mechanism accommodating portion 24. This knob lever 55 is linked with the actuation member 52, and is coupled, via the cable 31 of the conduit 32, to the locking knob (illustration omitted) for locking and unlocking operation provided on the intra-vehicle side of the door. When the locking knob is operated, the actuation member 52 moves upward or downward, and the above described locking and unlocking lever 19 linked with this actuation member 52 is switched over between the locked state and unlocked state.

The inside lever 57 is freely rotatably supported pivotally by the support shaft 56 provided in a protruding manner at the central portion at the lower portion of the operation mechanism accommodating portion 24. This inside lever 57 is coupled, via the cable 33 of the conduit 34, to an operation handle (illustration omitted) on the intra-vehicle side. The inside lever 57 pivots in a lock releasing direction (anti-clockwise in FIG. 7), when the operation handle on the intra-vehicle side is operated for opening of the door.

A key lever 59 is installed in an attachment hole 58 provided in an upper end portion on a rear portion side of the operation mechanism accommodating portion 24. A coupling arm portion 59a of this key lever 59 protruding to the extra-vehicle side of the first case 25 is linked with a key cylinder (illustration omitted) of the door. A linking plate 59b, which is linkable with the actuation member 52 and is roughly fan-shaped, is formed forward at an end portion on the intra-vehicle side of the key lever 59. In a front end portion of a surface on the intra-vehicle side of the linking plate 59b, a concave portion 59c, which is in a circumferential direction and is arc-shaped, is formed. A protruding portion 521, which is provided in a protruding manner at an upper end portion of the actuation member 52 and is in the outward direction of the vehicle, is fitted into this concave portion 59c, from the intra-vehicle side thereof.

When the locking and unlocking lever 19 is in the locked state, if the key cylinder is operated for unlocking, the key lever 59 pivots clockwise by a predetermined amount from a neutral position (position illustrated in FIG. 7), and an upper stepped portion 59d in the concave portion 59c of the key lever 59 abuts against the protruding portion 521 of the actuation member 52 from above. Thereby, the actuation member 52 is moved to the lower unlocked position (position illustrated in FIG. 7) from the upper locked position,

and the locking and unlocking lever 19 is switched over to the unlocked state via the actuation member 52.

Further, when the locking and unlocking lever 19 is in the unlocked state, if the key cylinder is operated for locking, the key lever 59 pivots anticlockwise by a predetermined amount from the neutral position and a lower stepped portion 59d in the concave portion 59c abuts against the protruding portion 521 from below. Thereby, the actuation member 52 is moved to the upper locked position from the lower unlocked position, and the locking and unlocking lever 19 is switched over to the locked state via the actuation member 52. This switch over operation between the locked and unlocked positions is detected by the rotary switch 60 attached to the rotary switch attachment portion 463 of the above described switch plate 46.

When the actuation member 52 moves to the locked position and the unlocked position, the limit switch 61 attached to the limit switch attachment portion 464 at the intermediate portion of the switch plate 46 is actuated and the motor 48 of the actuator 4 is stopped. That is, as illustrated in FIG. 7, when the actuation member 52 moves to the locked position and the unlocked position, an expandable and contractible protruding portion 61a at a distal end of the limit switch 61 comes in contact with an actuation protruding portion 522 provided in a protruding manner on a side surface on the extra-vehicle side of the actuation member 52. Thereby, an ON or OFF stop signal that stops the motor 48 is generated.

As illustrated in FIG. 1, at a central portion of the cover 27, a shaft hole 62 is provided, and an override lever 63 linked with the inside lever 57 is pivotally supported by this shaft hole 62. Regardless of a state of the locking and unlocking mechanism, the override lever 63 allows the door to be opened by releasing the engaged state of the engagement mechanism 9.

The driving portion 50 of the worm wheel 51 is formed of: a lock drive protruding portion 501a that is able to move the actuation member 52 to the locked position; an unlock drive protruding portion 501b that is adjacent to the lock drive protruding portion 501a and is able to move the actuation member 52 to the unlocked position; and two stoppage protruding portions 501c and 501d that are adjacent to each other on an opposite side of the lock drive protruding portion 501a and the unlock drive protruding portion 501b and are able to stop rotation of the worm wheel 51 and driving portion 50.

The lock drive protruding portion 501a, the unlock drive protruding portion 501b, and the two stoppage protruding portions 501c and 501d are formed so as to center around the support shaft 53, extend toward a circumference of the worm wheel 51, and be separated from one another by 90 degrees in the circumferential direction to form a cross-shape in their side view. Lengths of the respective protruding portions 501a to 501d in the radial direction are less than a radius of the worm wheel 51. Further, the lock drive protruding portion 501a and the unlock drive protruding portion 501b have lengths to be able to move the actuation member 52 to the upper locked position and the lower unlocked position.

At an upper end portion of the actuation member 52, the upper end portion being opposite to the driving portion 50, a concave portion 64, which is open on the driving portion 50 side, is formed, and a buffer member 65 with a silencing function is fixed in the concave portion 64. In the buffer member 65, a concave portion 65a is formed, which is open on the driving portion 50 side, from and into which the lock drive protruding portion 501a and the unlock drive protruding portion 501b are able to exit and enter, and which is

C-shaped in its side view. Upper and lower opposite surfaces of this concave portion **65a** are driven surfaces **65b** and **65b**, against which the lock drive protruding portion **501a** and the unlock drive protruding portion **501b** are respectively able to abut.

As illustrated in detail in FIG. 21, a depth dimension of the concave portion **65a** has a size such that distal ends of the lock drive protruding portion **501a** and the unlock drive protruding portion **501b** are able to rotate without contacting a deep surface of the concave portion **65a** when the driving portion **50** rotates. Further, a vertical width dimension of the concave portion **65a** has a size, such that the lock drive protruding portion **501a** and the unlock drive protruding portion **501b** go thereinto simultaneously when the actuation member **52** is moved upwards or downwards in association with rotation of the driving portion **50**. The buffer member **65** is formed of, for example, a polyester elastomer (trade name: Hytrel) having appropriate hardness and elasticity.

Next, actions of the actuator **4** will be described with reference to FIG. 21. In FIG. 21, (a) to (d) illustrate a case where the actuation member **52** in the unlocked position is moved to the locked position. FIG. 21(a) is an actuation start position in this case, that is, a state where the actuation member **52** is in the lower unlocked position, and the motor **48** of the actuator **4** is being stopped by a stop signal of the above described limit switch **61**. In the state of FIG. 21(a), the lock drive protruding portion **501a** in the driving portion **50** has gone inside the concave portion **65a**, and the upper stoppage protruding portion **501d** adjacent to this lock drive protruding portion **501a** has abutted against a front surface of an upper portion of the buffer member **65** opposite thereto.

In the state of FIG. 21(a), for example, when the motor **48** of the actuator **4** is normally rotated by operation of the remote control switch or the like, as illustrated in FIG. 21(b), the worm wheel **51** and the driving portion **50** start to rotate clockwise. Thereby, the lock drive protruding portion **501a** that has gone into the concave portion **65a** abuts against a lower surface of an upper driven surface **65b** of the concave portion **65a** from below. Simultaneously therewith, the unlock drive protruding portion **501b** adjacent to the lock drive protruding portion **501a** also starts to advance into the concave portion **65a**.

When the worm wheel **51** and the driving portion **50** are further rotated clockwise from this state, as illustrated in FIG. 21(c), by rotational drive force of the lock drive protruding portion **501a**, the actuation member **52** is pushed up. The upward movement of the actuation member **52** continues until immediately before the distal end of the lock drive protruding portion **501a** comes off from the upper driven surface **65b**, and this state being an upper bound fully pressed position of the actuation member **52**, the actuation member **52** is moved upward to the unlocked position. The unlock drive protruding portion **501b** deeply advances into the concave portion **65a**.

When the worm wheel **51** and driving portion **50** are rotated clockwise a little from the state illustrated in FIG. 21(c), as illustrated in FIG. 21(d), the distal end of the lock drive protruding portion **501a** comes off from the upper driven surface **65b**, the stoppage protruding portion **501c** on the opposite side of the lock drive protruding portion **501a** abuts against a front surface of a lower portion of the buffer member **65** opposite thereto, and the driving portion **50** stops at the locked position. Simultaneously with this abutment, the above described limit switch **61** is actuated, and by a stop signal generated thereby, the motor **48** is stopped, and actuation of the actuator **4** is ended. When the actuation

member **52** is moved to the upper locked position by the actuator **4**, the locking and unlocking lever **19** linked with the actuation member **52** is switched over to the locked state, and thereby opening operation of the door is disabled.

5 In FIG. 21, (e) to (g) illustrate a case where the actuation member **52** is moved from the locked position to the unlocked position. In a state of FIG. 21(d), for example, when the motor **48** is reversely rotated by operation of the remote control switch or the like, as illustrated in FIG. 21(e), 10 the worm wheel **51** and the driving portion **50** start to rotate anticlockwise. Thereby, the unlock drive protruding portion **501b**, which has gone into the concave portion **65a** and has been stopping, abuts against an upper surface of the driven surface **65b** of a lower portion of the concave portion **65a** from above. Simultaneously therewith, the lock drive protruding portion **501a** also starts to advance into the concave portion **65a**.

When the worm wheel **51** and the driving portion **50** are further rotated anticlockwise from this state, as illustrated in 20 FIG. 21(f), by rotational drive force of the unlock drive protruding portion **501b**, the actuation member **52** is pushed down. The downward movement of the actuation member **52** continues until immediately before the distal end of the unlock drive protruding portion **501b** comes off from a lower driven surface **65b**, and this state being a lower bound fully pressed position of the actuation member **52**, the actuation member is moved down to the unlocked position. The lock drive protruding portion **501a** deeply advances into the concave portion **65a**.

When the worm wheel **51** and the driving portion **50** are further rotated anticlockwise a little from the state illustrated in FIG. 21(f), as illustrated in FIG. 21(g), the distal end of the unlock drive protruding portion **501b** comes off from the lower driven surface **65b**, the stoppage protruding portion **501d** on the opposite side of the unlock drive protruding portion **501b** abuts against the front surface of the upper portion of the buffer member **65** opposite thereto, and the driving portion **50** stops at the unlocked position. Simultaneously with this abutment, the above described limit switch 30 **61** is actuated, and by a stop signal generated thereby, the motor **48** is stopped, and actuation of the actuator **4** is ended. This actuation end position and the actuation start position in FIG. 21(a) are of the same state. Therefore, when the motor **48** of the actuator **4** is normally rotated, the actuation member **52** is able to be moved from the unlocked position to the locked position. When the actuation member **52** is moved to the lower unlocked position by the actuator **4**, the locking and unlocking lever **19** linked with the actuation member **52** is also switched over to the unlocked state, and thereby opening operation of the door is enabled.

As described above, the driving portion **50**, which is provided in the worm wheel **51** and moves the actuation member **52** to the locked position and the unlocked position, is formed of the lock drive protruding portion **501a**, the unlock drive protruding portion **501b**, and the two stoppage protruding portions **501c** and **501d**, which are separated from one another by 90 degrees in the circumferential direction. Further, when the actuation member **52** is stopping at the locked position and the unlocked position, the lock drive protruding portion **501a** and the unlock drive protruding portion **501b** are positioned in the concave portion **65a** of the actuation member **52**, and during the movement of the actuation member **52** to the locked position or the unlocked position, the unlock drive protruding portion **501b** or the lock drive protruding portion **501a** also advances into the concave portion **65a** simultaneously therewith. Further, when the driving portion **50** normally and reversely rotates,

the actuation member **52** is moved to the locked position and the unlocked position by the lock drive protruding portion **501a** and the unlock drive protruding portion **501b**, and when the actuation member **52** moves to the locked position and unlocked position, the stoppage protruding portions **501c** and **501d** abut against the actuation member **52** so that rotation of the driving portion **50** is stopped. Thereby, an operation time of the motor **48** and a rotational angle of the worm wheel **51** by the actuator **4** become small, the operation time and rotational angle in and by which the actuation member **52** and the locking and unlocking lever **19** linked to the actuation member **52** are moved from the unlocked position to the locked position or reversely thereto and are stopped. As a result, the operation time of the actuator **4**, from the operation on an operation switch, such as the remote control switch, to the switch-over of the door latch device **1** to the locked state and the unlocked state, is shortened.

Further, since each of the protruding portions 501a to 501d abuts against the buffer member 65 provided in the actuation member 52 and having the silencing function, impact noise upon the abutment is small.

Furthermore, since the actuation start position (FIG. 21(a)) before the actuation member 52 is actuated from the unlocked position to the locked position and the actuation end position (FIG. 21(g)) after the actuation member 52 has been actuated from the locked position to the unlocked position are of the same state, the worm wheel 51 does not need to be returned to an initial position after being moved to the respective positions, and a spring or the like for the return is also not needed.

As described above, in the door latch device of this embodiment, the first to fourth positioning portions 262, 263, 264, and 265 are provided on the rear surface of the second case 26 and the side surface on the intra-vehicle side of the cover 27, so that positioning is achieved when the waterproof seal 45 is stuck thereto. Thereby, the sticking start position and the sticking position for the waterproof seal 45 are clarified, the waterproof seal 45 is able to be positioned and accurately stuck to the fixed position on the engagement unit 2 and the cover 27, and workability upon the sticking is improved.

Further, on the rear surface top portion of the top waterproof cover 42, the water shielding wall portion 423, which guides rainwater flowing down from the rear surface of the top waterproof cover 42 in the outward direction of the vehicle, is provided, and the upper seal sticking portion 261 of the second case 26 has the function as the water shielding wall that guides rainwater flowing down from the rear surface of the top waterproof cover 42 to the extra-vehicle side, and thus the amount of rainwater flowing to the rear surface side of the engagement unit becomes extremely small. Therefore, there is no need to bend the upper seal portion 45a stuck to the rear surface side of the engagement unit 2 downwards to extend the upper seal portion 45a to the intermediate portion of the engagement unit 2 as conventionally done, and as compared with a waterproof seal attached to a conventional door latch device, the length of the waterproof seal 45 is able to be shortened and workability upon the sticking thereof is able to be improved.

Furthermore, since rainwater guided by the water shielding wall portion 423 of the top waterproof cover 42 to the intra-vehicle side of the cover 27 is guided to the lower front of the cover 27 by the upper surface of the third positioning

portion 264, the amount of rainwater flowing towards the side seal portion 45b becomes extremely small.

 20 The invention claimed is:
 1. A vehicle door latch device, comprising:
 a body in which an engagement mechanism is accommodated, the engagement mechanism being configured to restrain a door in a closed position by engaging with a striker on a vehicle body side, the body including a striker advancing groove, into which the striker is able to advance when the door is closed;
 25 a housing that has: an operation mechanism accommodating portion in which various components is accommodated; and a body accommodating portion provided consecutively on and substantially perpendicularly to the operation mechanism accommodating portion and configured to cover the body;
 a cover configured to close an opening of the operation mechanism accommodating portion; and a waterproof seal for preventing rainwater from entering the body, wherein
 30 a seal sticking portion, at which an upper seal portion of the waterproof seal is stuck, is provided upward in a protruding manner at an upper portion of the body accommodating portion that is above the striker advancing groove;
 a seal sticking portion, at which an upper seal portion of the waterproof seal is stuck, is provided at a lower edge and a side edge of the seal sticking portion, the side edge being on an extra-vehicle side, the upper positioning unit being configured to receive and position a lower surface and an end face of the upper seal portion, the end face being on the extra-vehicle side, the upper positioning unit comprising a lower edge on the cover that is continuous with the lower edge of the seal sticking portion;
 35 a side positioning unit, which is configured to position a side seal portion of the waterproof seal to be directed diagonally downward, is provided on a surface on an intra-vehicle side of the cover where the side seal portion is stuck, the side seal being provided in a continuous manner at the upper seal portion and being bent towards the cover; and
 40 a top waterproof cover, which is configured to cover a coupling portion between the operation mechanism accommodating portion and the cover, is provided above the housing, and a water shielding wall portion, which is configured to guide rainwater flowing down towards the body from an upper surface of the top waterproof cover in an intra-extra vehicle direction, is provided upward at an end portion on the body side of the top waterproof cover;
 45 a top waterproof cover, which is configured to cover a coupling portion between the operation mechanism accommodating portion and the cover, is provided above the housing, and a water shielding wall portion, which is configured to guide rainwater flowing down towards the body from an upper surface of the top waterproof cover in an intra-extra vehicle direction, is provided upward at an end portion on the body side of the top waterproof cover;
 50 a top waterproof cover, which is configured to cover a coupling portion between the operation mechanism accommodating portion and the cover, is provided above the housing, and a water shielding wall portion, which is configured to guide rainwater flowing down towards the body from an upper surface of the top waterproof cover in an intra-extra vehicle direction, is provided upward at an end portion on the body side of the top waterproof cover;
 55 a top waterproof cover, which is configured to cover a coupling portion between the operation mechanism accommodating portion and the cover, is provided above the housing, and a water shielding wall portion, which is configured to guide rainwater flowing down towards the body from an upper surface of the top waterproof cover in an intra-extra vehicle direction, is provided upward at an end portion on the body side of the top waterproof cover;
 60 a top waterproof cover, which is configured to cover a coupling portion between the operation mechanism accommodating portion and the cover, is provided above the housing, and a water shielding wall portion, which is configured to guide rainwater flowing down towards the body from an upper surface of the top waterproof cover in an intra-extra vehicle direction, is provided upward at an end portion on the body side of the top waterproof cover;
 65 a top waterproof cover, which is configured to cover a coupling portion between the operation mechanism accommodating portion and the cover, is provided above the housing, and a water shielding wall portion, which is configured to guide rainwater flowing down towards the body from an upper surface of the top waterproof cover in an intra-extra vehicle direction, is provided upward at an end portion on the body side of the top waterproof cover.

2. The vehicle door latch device according to claim 1, wherein a side end on the extra-vehicle side of the water shielding wall portion is made adjacent to or to abut against a side end on the intra-vehicle side of the seal sticking portion such that rainwater is guided in an outward direction 5 of a vehicle via the water shielding wall portion and the seal sticking portion.

3. The vehicle door latch device according to claim 1, wherein a side end on the intra-vehicle side of the water shielding wall portion is made continuous with an upper end 10 of the side positioning unit such that rainwater guided to the intra-vehicle side by the water shielding wall portion is guided by an upper surface of the side positioning unit and flown down from the cover.

4. The vehicle door latch device according to claim 2, 15 wherein a side end on the intra-vehicle side of the water shielding wall portion is made continuous with an upper end of the side positioning unit such that rainwater guided to the intra-vehicle side by the water shielding wall portion is guided by an upper surface of the side positioning unit and 20 flown down from the cover.
